UNITED STATES PATENT OFFICE.

ARTHUR KOPPERUD, OF MILWAUKEE, WISCONSIN.

DESIGN FOR A RADIATOR CAP.

Application filed May 26, 1922. Serial No. 2,429. Term of patent 7 years.

To all whom it may concern:

Be it known that I, ARTHUR KOPPERUD, a citizen of the United States, residing at Milwaukee, in the county of Milwaukee and State of Wisconsin, have invented a new, original, and ornamental Design for a Radiator Cap, of which the following is a specification, reference being had to the accompanying drawing, forming part thereof.

Figure 1 is a rear elevation of the radiator cap showing my new design, and

Figure 2 is a side elevation thereof.

I claim:

The ornamental design for a radiator cap, as shown.

In testimony that I claim the foregoing I have hereunto set my hand at Milwaukee, in the county of Milwaukee and State of Wisconsin.

ARTHUR KOPPERUD.
